UNITED STATES PATENT OFFICE.

CHARLES W. WILSON, OF EDGEWOOD, ILLINOIS.

TOY.

1,016,662.

Specification of Letters Patent.

Patented Feb. 6, 1912.

Application filed April 12, 1909, Serial No. 489,383. Renewed October 23, 1911. Serial No. 656,219.

To all whom it may concern:

Be it known that I, CHARLES W. WILSON, citizen of the United States, residing at Edgewood, in the county of Effingham and 5 State of Illinois, have invented certain new and useful Improvements in Toys, of which the following is a specification.

This invention relates to improvements in toys and embraces the construction of a toy 10 consisting of a series of flexibly united blocks bearing pictures or formed to simulate miniature men.

One of the objects of the invention is the construction of a toy, consisting of a series 15 of flexibly united tumbling blocks, simulating miniature men, so arranged that the falling of one block against the other will produce a novel and amusing effect.

With the above and other objects in view 20 the invention consists in certain combinations, constructions and arrangements of parts, clearly described in the following specification and clearly illustrated in the accompanying drawings, in which,

25 Figure 1 is a front elevation showing the blocks extended, Fig. 2 is a side elevation showing the blocks in angular positions relative to each other, or ready to be tumbled, Fig. 3 is a central longitudinal sectional view of the blocks in extended positions, Fig. 4 is a side elevation showing three of the blocks in line with each other and one of the blocks at right angles to the three blocks, in position to be tumbled, and 30 Fig. 5 is a perspective view showing the toy partly collapsed.

Referring to the accompanying drawings illustrating the invention 1 denotes the top or upper block, 2 the next or adjoining block, 3 the third block, which adjoins 2, and 4 the lower or last block, which adjoins 3. The three upper blocks, 1, 2 and 3 are preferably formed to simulate miniature men. The blocks 1 and 2 are provided with 45 legs 5 and 6, respectively, which are spaced apart to form approximately V-shaped spaces. The block 3 is provided with legs 10 and 11, like the legs of the blocks 1 and 2. The block 2 is formed with a rounded 50 portion or head 7 which abuts against the terminals of the legs 5, and the block 3 is formed with a rounded portion or head 8 which abuts against the legs 6. The lower block 4 is formed with a rounded end 9 55 which abuts against the legs 10 and 11 of

the block 3, and with an inwardly curved portion 12.

In order to unite the four blocks together three tapes, flexible in nature, are used. A central tape 13 is secured to the rounded 60 head 9 of the lower block, engages one side of the block 3, is passed between the legs of the block 2 and engages the side of the block 2 opposite the side of the block 3 engaged by the tape. The central tape 13 65 is then passed between the legs 5 of the block 1 and engages the side of this block opposite to the side engaged on the block 2, or like the side engaged on the block 3, and is secured at its upper end to the head or 70 rounded portion of the block 1, which head or rounded portion is like that of the blocks 2 and 3. It will thus be seen that the tape engages with alternate sides of the blocks. Screws 20 serve to hold the ends of the tape 75 to the blocks 4 and 1, and to the upper ends of the blocks 3 and 2, as shown in Fig. 2. In addition to the central tape 13 two other tapes 14 and 15 are employed. Both of these tapes are secured to the lower ends of 80 the block 4 at points outwardly of the point where the central tape 13 is fastened. The tapes 14 and 15 then engage the side of the lower block 4 and are fastened to the terminals of the legs of the block 3, engaging one 85 side of this block, opposite to the side engaged on the lower block by the two tapes. The tapes are then fastened by screws 20, which fasten the tapes at all points where they are secured, to the terminals of the legs 90 6 of the block 2, and engaging one side of the block 2 extend above this block to engage with the terminals of the legs 5 of the block 1.

When the toy is placed in the position 95 shown in Fig. 1 and the upper block 1 is tilted in the manner shown in Fig. 2 the three lower blocks or men will tumble on the holding tapes so as to occupy inverted positions thereon. By repeating the operation 100 the men or blocks may be caused to resume their former positions, and by again repeating the operation the blocks may again be inverted, and so on indefinitely. The blocks may be arranged to represent 105 men, animals or birds, and may be arranged to represent different figures of a comical group. As the blocks are so formed that the engaging ends have excellent bearings and a single tape extends centrally of 110

the blocks, the operation of the toy is rendered very easy.

I claim—

In a tumbling toy, a series of blocks the 5 larger portion of the blocks having rounded heads and spaced legs, a central tape secured to the lower block at its upper end, engaging alternate sides of the intermediate blocks and secured to the upper end of 10 the upper block, said tape crossing the intermediate blocks and being secured to the said blocks at the upper ends thereof, and tapes on each side of the central tape, said tapes having their lower ends secured to the

lower end of the lower block and their upper ends secured to the leg terminals of the upper blocks, said tapes crossing the intermediate blocks and engaging with alternate sides of said intermediate blocks and being secured to the leg terminals of said intermediate blocks. 15 20

In testimony whereof I affix my signature, in presence of two witnesses.

CHARLES W. WILSON.
